UNITED STATES PATENT OFFICE

FRED K. HENDRICKSON, OF WORCESTER, MASSACHUSETTS, ASSIGNOR TO WHITIN MACHINE WORKS, OF WHITINSVILLE, MASSACHUSETTS, A CORPORATION OF MASSACHUSETTS

SCAVENGER MECHANISM FOR SPINNING FRAMES

Application filed May 3, 1929. Serial No. 360,216.

This invention relates to machines for spinning textile fibres, such as cotton or wool, and relates more particularly to the means provided for receiving the yarn or 5 roving when one or more ends of yarn are broken.

It is the object of my invention to provide a scavenger or clearer roll for a spinning frame so constructed that the roll will be 10 continuously rotated during the normal operation of the machine, catching and winding up the yarn or roving on breakage of yarn ends. I further provide driving connections for the scavenger roll permitting the 15 roll to yield, and come to rest in the event that the hands or clothing of the operator are caught thereby.

My invention further relates to arrangements and combinations of parts which will 20 be hereinafter described and more particularly pointed out in the appended claim.

A preferred form of the invention is shown in the drawings in which

Fig. 1 is a front elevation of parts of a 25 wool spinning frame embodying my improvements;

Fig. 2 is an enlarged sectional side elevation, taken along the line 2—2 in Fig. 1;

Fig. 3 is a detail end view, looking in the 30 direction of the arrow 3 in Fig. 1, and

Fig. 4 is a detail sectional view, taken along the line 4—4 in Fig. 3.

Referring to the drawings, I have shown 35 portions of a wool spinning frame, including frame members 10 in which twisting heads 11 are rotatably mounted. Drawing rolls 12 and 13 are positioned below the twisting heads 11 and receive the yarn Y as it passes therefrom.

The front drawing roll 12 is positively 40 rotated in any suitable manner, as by bevel gears 15 and 16 from a driving shaft 17. The yarn Y passes downward and forward from the drawing rolls 12 and 13 to a guide board 18 and thence downward to spinning rings 19 and bobbins 20.

A shaft 30 is rotatably mounted in bearings 31 and extends lengthwise of the machine below the drawing rolls 12 and 13 and 45 preferably substantially under the roll 13.

The shaft 30 is provided with a series of scavenger rolls 34, spaced to correspond with the twisting heads 11.

The rolls 34 are preferably covered with fabric or other material adapted to easily 55 catch and retain a broken end of yarn or roving, and the front portion of the periphery of the roll is rather closely adjacent the path of the yarn Y as it is drawn downward from the drawing rolls 12 and 13 to the guide 60 board 18.

When a yarn end is broken, the loose yarn or roving readily engages the adjacent scavenger roll 34 and is wound up thereon, thus preventing the yarn becoming entangled 65 with adjacent roving and causing breakage of additional yarn ends.

The shaft 30 is provided with a gear 40, engaged by a pinion 41 on the front drawing roll or shaft 12. The pinion 41 is positively 70 driven but the gear 40 is yieldingly connected with the shaft 30, these connections being best shown in Figs. 3 and 4.

The gear 40 is rotatably mounted on the hub portion 42 of a collar 44, secured to the 75 shaft 30 by a headless set screw 45 or in any suitable or convenient manner. A friction disc 47 is inserted between adjacent side portions of the gear 40 and collar 44, the disc being held from rotation relative to the collar 44 by a pin or key 48. Springs 49 press the disc 47 against the side surface of the gear 40, and the thrust of the springs 49 is received by a collar 50, mounted on the shaft 30 and secured to the collar 44 by screws 52. 80

With this construction the shaft 30 and scavenger rolls 34 are normally continuously rotated by the gear 40 through the friction driving connection above described. It somewhat frequently happens, however, that the operator, while endeavoring to remove the accumulation of yarn or roving from a rotating scavenger roll, has his fingers or clothing caught on the roll, or between the roll and the brackets 54 by which the rear drawing rolls 13 are supported. When this happens, serious injury would very probably result if it were not for the provision of the friction driving connection between the gear 40 and the shaft 30. This connection adds 85 10?

materially to the safety of operation of the machine and substantially reduces the chance for accident due to engagement with the scavenger rolls.

Having thus described my invention and the advantages thereof, I do not wish to be limited to the details herein disclosed otherwise than as set forth in the claims, but what I claim is:—

In a spinning frame, a drawing roll shaft, drawing rolls thereon, additional drawing rolls engaging therewith, a scavenger roll shaft, a scavenger roll thereon below said drawing rolls, and immediately adjacent the normal path of yarn from the drawing rolls, means to rotate said scavenger roll in a definite speed relation to the rotation of said drawing rolls, said rotating means including an extension on each of said shafts at the side of the respective rolls and gearing connecting said extensions, said gearing including a yielding connection permitting said scavenger roll to be stopped while said drawing roll continues in rotation.

In testimony whereof I have hereunto affixed my signature.

FRED K. HENDRICKSON.
